(57) CLAIM

The ornamental design for a case for packet of chewing-gum sticks, as shown.

DESCRIPTION

FIG. 1 is a side view of the case of the present invention, with the case lying on its back;

FIG. 2 is a side view of the case of the present invention, with the top open, with the case resting on its bottom;

FIG. 3 is the same view as FIG. 2, but with the case closed;

FIG. 4 is a front view of the closed case;

FIG. 5 is a back view of the closed case;

FIG. 6 is a top view of the closed case (the bottom view is identical);

FIG. 7 is a three quarter perspective view of the open case, viewed from the left front;

FIG. 8 is a three quarter perspective view of the open case, viewed from the back right;

FIG. 9 is a front view of the open case;

FIG. 10 is a three quarter perspective view of the case with the lid removed, viewed from the front left, with the lid viewed from the back right;

FIG. 11 is a three quarter perspective view of the closed case laying on its back;

FIG. 12 is a top view of the open case; and,

FIG. 13 is a back view of the open case.
